UNITED STATES PATENT OFFICE.

EMIL WAGENER, OF DAHLHAUSEN-ON-THE-RUHR, GERMANY.

REGENERATIVE COKE-OVEN.

977,348.

Specification of Letters Patent. Patented Nov. 29, 1910.

Application filed September 27, 1910. Serial No. 584,085.

To all whom it may concern:

Be it known that I, EMIL WAGENER, a subject of the Emperor of Germany, residing at Dahlhausen-on-the-Ruhr, Westphalia, 5 Kingdom of Prussia, Germany, have invented a certain new and useful Improvement in Regenerative Coke-Ovens, of which the following is a true and exact description, reference being had to the accompanying drawings, which form a part thereof.

My present invention relates to regenerative coke ovens, and the object of the invention is to provide an arrangement of heating flues and air and gas supply connections, 15 whereby flames and hot products of combustion are caused to flow through the heating flues, first in one direction and then reversely, as the regenerator connections are adjusted, without reversal or alteration in 20 the flow of the gas which is burned.

A further object of the invention is to provide an arrangement whereby the hot air from the regenerator may be supplemented by warm air from passages in the oven 25 structure.

The various features of novelty which characterize the invention are pointed out with particularity in the claims annexed to and forming a part of this specification. 30 For a better understanding of the invention, however, and the advantages possessed by it, reference should be had to the accompanying drawings and descriptive matter, in which I have illustrated and described 35 one of the forms in which the invention may be embodied.

Of the drawings: Figure 1 is a section taken transversely to the ovens, the left hand portion being taken on the line A B 40 and the right hand portion on the line C D of Fig. 2. Fig. 2 is a longitudinal section taken along the line E F of Fig. 1, and Fig. 3 is a horizontal section taken along the line G H of Fig. 2.

In the construction shown by the drawings, divided sole passages or channels 2 and 13 are formed underneath the oven chambers 20. In the wall between each adjacent pair of oven chambers are formed vertical 50 heating flues arranged in groups, each group consisting of a flue 3 communicating at its lower end with a sole channel 2; a flue 10 communicating at its upper end with the upper end of flue 3, a flue 11 55 communicating at its lower end with the lower end of flue 10 and a flue 12

communicating at its upper end with the upper end of flue 11, and at its lower end with a sole passage or channel 13. The regenerators, the construction of which is not 60 shown by the drawings, but which may be of usual form, are connected, one to each sole channel 2 by passages 1 at the left hand side of the structure as seen in Fig. 2 and the other by passages 14 to the right hand 65 ends of the sole channels 13.

With the direction of the draft of the heating gases as shown in the figures, the hot air of combustion enters from the left regenerator—which can be regulated separately for each wall—through the channels 1 into the sole channels 2 and rises for each heating group through its flue 3. The heating gas is supplied to the heating flues from above through an upper main pipe 4, gas 75 pipes 5 and nozzles 6 and from below through a lower main pipe 7, gas pipes 8 and nozzles 9 and the quantity can be regulate at each nozzle. The hot air from the flues 3 is mixed at the upper turning point with the heating gas 80 from the nozzles 6. The burning gas descends with a surplus of air in the flues 10. At the lower turning point the gas from nozzles 9 takes up its air of combustion, or at least a part of same, from the passage 85 ways or tunnels beneath the retorts through the channels into which the nozzles 9 extend. The heating gas rising in the flues 11 receives at the next upper turning point some more gas from burner pipes 6 and travels 90 through flues 12 sole channels 13 and flues 14, to the regenerator at the right, where it delivers its heat to the checkerwork. In addition to the groups of flues referred to, there are two other flues 15, in the wall at 95 the side of each oven, one at each end. The two lower burner pipes 9 at the ends heat the two end flues 15, the air supporting combustion therein being supplied through the channel at the lower end of the flues into 100 which their nozzles 9 extend. The gas flow through the flues 15 is continuously in the same direction, the gases from the flues 15 passing out of the flues 15 at their upper ends into the upper ends of the adjacent 105 flues 3.

After operating for the usual or desired period with one direction of the draft, the latter is reversed by turning the usual valves, or like draft shifting devices. The hot air 110 then enters from the regenerator on the right through flues 14 into the channels 13 and

from there passes into the wall flues 12. The direction of the flames in the flues of each group is then opposite to the directions shown in the drawing. The heating gases 5 pass through the flues 11, 10, 3, sole channels 2 and flues 1 to the regenerator at the left and all the gas burners continue burning as before.

Having now described my invention, what 10 I claim as new and desire to secure by Letters Patent, is:

1. In a regenerative coke oven structure, the combination with the retorts, of sole channels beneath the retorts, vertical heating flues at the side of each retort arranged in groups in which adjacent flues are connected together alternately at top and bottom, with the end flues of each group connected at their lower ends, one to one and the other 20 to another of said sole channels, whereby each of said flue groups forms a continuously open channel between a pair of said sole channels, regenerative connections to said sole channels whereby the flow of air 25 through said sole channels and the groups of flues connecting them may be reversed, continuously operating gas burners arranged at the tops of said end flues of each group

and at the lower end of each of the two flues of each group adjacent the end flues thereof. 30

2. In a regenerative coke oven structure, the combination with the retorts of sole channels beneath the retorts, vertical heating flues at the side of each retort arranged in groups in which adjacent flues are connected together alternately at top and bottom, with the end flues of each group connected at their lower ends, one to one and the other to another of said sole channels, whereby each of said flue groups forms a 40 continuously open channel between a pair of said sole channels, regenerative connections whereby the flow of air through said sole channels and the groups of flues connecting them may be reversed, continuously operating gas burners opening into the passage formed by each group of connected flues at a distance from the ends thereof, and air supply channels in the oven structure opening into said passages at distances from 45 their ends through which atmospheric air may pass into said passages. 50
